(57) **CLAIM**

We claim the ornamental design for a locker organizer, as shown and described.

DESCRIPTION

FIG. 1 is a top, front, and right side perspective view of a locker organizer showing our new design;

FIG. 2 is an enlarged front elevational view thereof;

FIG. 3 is an enlarged top plan view thereof;

FIG. 4 is an enlarged right side elevational view thereof;

FIG. 5 is an enlarged left side elevational view thereof;

FIG. 6 is an enlarged rear elevational view thereof; and,

FIG. 7 is an enlarged bottom plan view thereof.

The broken-line disclosure in the views is for illustrative purposes only and forms no part of the claimed design.
